OIL-CHAMBER FOR ELECTRIC CLOCKS

Walter Kohlhagen, Waterbury, Conn., assignor to
 The Waterbury Clock Company, Waterbury,
 Conn., a corporation

Application May 24, 1935, Serial No. 23,197

6 Claims. (Cl. 308—36.1)

This invention relates to an improvement in oil-chambers, and particularly to oil-chambers for electric clocks and the like.

Oil-chambers for electric clocks, as generally heretofore constructed, have been subject to relatively-rapid loss of the oil initially deposited therein. This loss has been occasioned largely by capillary action, which slowly but continually effects the withdrawal of the oil from within 10 the oil-chamber to the outside thereof via the bearing-passage or passages through which one or more shafts extend.

One of the objects of the present invention is to provide an oil-chamber construction which, 15 while insuring adequate lubrication to such shafts as may project therefrom, will prevent or minimize the oil leakage due to capillary action.

A further object is to provide an oil-chamber in which the bearing-passage or passages there- 20 of are assured of an adequate supply of oil without occasioning an objectionable outward pumping action which might ultimately drain the oil from the oil-chamber.

Another object is to provide a superior oil- 25 chamber construction in which the bearing-passage or passages leading therefrom and the rotary member or members mounted therein will coact to return only excess oil to the oil-chamber, and not deprive the coacting surfaces of 30 the requisite amount of lubrication.

With the above and other objects in view, as will appear to those skilled in the art from the following, considered in conjunction with the accompanying drawing and appended claims, the 35 present invention includes all features disclosed therein which are novel over the prior art.

In the accompanying drawing:

Fig. 1 is a vertical central sectional view of 40 a synchronous electric clock mechanism illustrating one form which the present invention may assume;

Fig. 2 is a sectional view taken on the line 2—2 of Fig. 1;

Fig. 3 is a central longitudinal sectional view 45 illustrating, on an enlarged scale, the right-hand bearing of the structure shown in Fig. 1; and

Fig. 4 is a central longitudinal sectional view illustrating another form which the present invention may assume.

50 The particular synchronous electric clock structure herein chosen for illustration includes a mounting-plate 10 having secured to its forward face, by means of screws 11, a cup-shaped housing 12, which may be of any approved form and may, for instance, be produced by die-

casting. Interposed between the rear face of the flange 13 of the housing 12 and the forward face of the mounting-plate 10 is a gasket 14, serving to prevent the leakage of a body of oil 5 contained within the closed chamber 16 within the aforesaid housing 12.

Tightly mounted in a passage 17 in the mounting-plate 10 and projecting both forwardly and rearwardly therefrom is a sleeve 18 having a relatively-large longitudinal passage 19 therein, 10 as shown particularly well in Fig. 1. The rear end of the passage 19 in the sleeve 18 is slightly enlarged to form a shoulder 20, against which is seated a rear bearing-bushing 21 held rigidly in place by burring the metal of the rear 15 end of the sleeve 18 thereover as at 22. The forward end of the sleeve 18 is similarly enlarged to provide an annular shoulder 23 against which a front bearing-bushing 24 is held by means of a swaged-over portion 25 of the forward end of the sleeve 18.

Mounted within and relatively-closely fitting the passage 19 in the sleeve 18 is a capillary-tube 19^a having an internally-threaded bore 19^b of such direction as to tend to return oil inwardly 25 toward the bearing-bushing 24. Extending through the internally-threaded bore 19^b of the capillary-tube 19^a and through the bearing-pas- 30 sages 26 and 27 respectively formed in the bushings 21 and 24, is a shaft 28, preferably smaller in 35 diameter than the diameter of the threaded bore 19^b of the capillary-tube 19^a. It has been found that satisfactory results are obtained when the threaded bore 19^b, above referred to, is substan- 40 tially .008" larger than the diameter of the said 45 shaft 28, to thus create a capillary space.

The shaft 28, just above referred to, mounts at its rear end a rotor 29 and may, for convenience of description, be designated as the power-input 40 shaft. The rotor 29 forms a feature of an elec- 45 tric motor which requires no detailed description other than to say that it includes a stator-structure 30 of iron or equivalent material and mounts a usual coil or solenoid 31.

The motor including the parts 29, 30 and 31 in 45 the present structure is intended to function as a synchronous electric motor to impart accurately-timed rotation to a shaft 32, which latter may be designated, for convenience of description, as the power-output shaft, inasmuch as it may serve to 50 drive a hand or pointer 33 or other suitable timing element.

The forward end of the power-input shaft 28, before referred to, rigidly mounts a pinion 34 meshing into and driving a gear-wheel 35 rotat- 55

ing as a unit with a pinion 36. The last-mentioned pinion 36 meshes into and drives a gear-wheel 37, rigidly attached to a pinion 38 which in turn meshes into and drives a gear-wheel 39, which latter, like the gear-wheels 35 and 37, before described, is rigidly secured to a complementary pinion, such as 40. The pinion 40 meshes into and drives a gear-wheel 41, meshing into and driving a pinion 42, rigidly attached to the rear 10 end of the power-output shaft 32, before referred to.

The hand or pointer 33 at the outer end of the shaft 32 may, for instance, constitute the seconds pointer of a synchronous electric clock, and for 15 the purpose of taking off power to drive a minute-pointer and an hour-pointer, the shaft 32 is provided about midway of its length with a pinion 43. The pinion 43, just referred to, when staked to the shaft 32, serves to restrain the inward axial 20 movement of the latter in a bearing-passage 44 extending through the forward wall of the cup-shaped housing 12, and through a rearwardly-extending boss 45 formed integral with the said wall.

25 From the foregoing, it will be seen that within the closed chamber 16 is provided a supply of lubricant 15 and a suitable gear-train enabling the power-input shaft 28 to effect the accurately-timed rotation of the power-output shaft at a 30 greatly-reduced speed.

The oil 15 within the closed chamber 16 will be distributed by the various gears and pinions to the bearing-passages 26, 27 and 44, and if unrestrained such oil would slowly but continuously 35 exude to the exterior of the structure through the bearing-passages 26 and 44, and ultimately drain the supply of oil from the said chamber 16.

To prevent the undue exuding of oil and at the same time insure the adequate lubrication of the 40 bearings, the interior surface of the bearing-bushing 21 is provided with a relatively-coarse 45 pitch helical oil-return groove 46, which, it is to be noted, communicates with the longitudinal passage 19 in the sleeve 18. The outer end of the oil-return groove 46 intersects the rear face of the bearing-bushing 21, but this feature is not essential inasmuch as the said groove may stop short of the rear face of the said bushing. The 50 steepness of the pitch of the oil-return groove 46 results in the formation of a spiral land-like bearing-surface of adequate area upon the interior surface of the passage 26 in the bushing 21.

In the course of time, as oil from the chamber 16 travels along the shaft 28 and tends to 55 move outwardly through the minute space between the periphery of the said shaft and the surface of the bearing-passage 26 in the bushing 21, the major portion of the said oil will be forced back through the helical oil-return passage 46 60 into the interior of the passage 19. This effect is accomplished by inclining the groove 46 in such direction with respect to the direction of rotation of the shaft 28, that the surface of the said shaft will tend to wipe the oil inwardly along the said 65 groove. The coaction of the surface of the shaft 28 and the groove 46, as above described, will return to the chamber 16 any excess oil, and thus prevent or minimize the outward leakage of lubricant without, however, depriving the bearing-passage 26 of sufficient oil to effectively minimize 70 wear.

In a manner similar to the treatment of the bearing-passage 26, the bearing-passage 44 in the housing 12 and its integral boss 45 may be 75 provided with a steep-pitch helical oil-return

groove 47, preferably communicating with the rear end of the said boss and hence with the interior of the chamber 16. In this instance, also, the direction of the helical oil-return groove 47 is such that the periphery of the power-output 5 shaft 32, in cooperating therewith, will tend to force excess oil rearwardly back into the chamber 16.

As shown in Fig. 4, a shaft 48 may be provided at spaced-apart points with steeply-inclined oil-return grooves 49 and 50 respectively cooperating with the interior bearing-surfaces of bearing-bushings 51 and 52, to prevent the undue escape of oil from an oil-chamber or reservoir 53 within a tubular body-member 54.

From the foregoing, it will be seen that in a simple way, the effect of capillary action in causing oil leakage is effectively counteracted by the coaction of a bearing-surface with a properly-inclined groove in a complementary bearing-surface, thus effectively solving one of the most troublesome of the problems which have long confronted the makers of electric clocks. It is appreciated in this connection that the average users of clocks cannot be relied upon to replenish 25 the oil-supply of an electric clock, with the result, in ordinary cases, that the bearings soon go dry and objectionable wear and noise result. By means of the present invention, the mechanism is assured of an adequate supply of lubricant 30 throughout a long period exceeding that which has heretofore been feasible.

The invention may be carried out in other specific ways than those herein set forth without departing from the spirit and essential characteristics of the invention, and the present embodiments are therefore to be considered in all respects as illustrative and not restrictive, and all changes coming within the meaning and equivalency range of the appended claims are intended 40 to be embraced therein.

I claim:

1. An oil-chamber construction of the class referred to, including: a housing-structure providing a closed oil-chamber therein, and having a bearing-passage leading from its interior to its exterior; and a shaft rotatably bearing directly in the bearing-passage of the said housing-structure; one at least of the coacting-surfaces of the said bearing-passage and the said shaft being provided with a helical oil-return groove, the convolutions of which are walled off from each other by flat-faced bearing-lands, which latter actually support the weight of the said shaft, the direction of relative rotation between the said shaft and the surface of the said bearing-passage being such that the coacting-surfaces effect the wiping of excess oil inwardly through the said helical oil-return groove toward the oil-chamber in the said housing-structure.

2. An oil-chamber construction of the class referred to, including: a housing-structure providing an oil-chamber therein, and having a bearing-passage leading from its interior to its exterior; and a shaft rotatably bearing directly in the bearing-passage of the said housing-structure; one at least of the coacting-surfaces of the said bearing-passage and the said shaft being provided with a helical oil-return groove leading to the interior of the oil-chamber within the said housing-structure, the convolutions of the said groove being walled off from each other by flat-faced bearing-lands, which latter actually support the weight of the said shaft, and the direction of relative rotation between the said

shaft and the said bearing-passage being such that the coating-surfaces effect the wiping of excess oil inwardly through the said helical groove into the oil-chamber in the said housing-structure.

5. An oil-chamber construction of the class referred to, including: a housing-structure providing a closed oil-chamber therein, and having a bearing-passage leading from its interior to its exterior, which bearing-passage is formed with a helical oil-return groove; and a shaft rotatably bearing directly in the bearing-passage of the said housing-structure; the convolutions of the said groove being walled off from each other by flat-faced bearing-lands, which latter actually support the weight of the said shaft; the direction of relative rotation between the said shaft and the said bearing-passage being such that the coating-surfaces effect the wiping of excess oil inwardly through the said helical groove toward the oil-chamber in the said housing-structure.

20. An oil-chamber construction of the class referred to, including: a housing-structure providing an oil-chamber therein, and having a bearing-passage leading from its interior to its exterior, which bearing-passage is formed with a helical oil-return groove connecting to the interior of the oil-chamber within the said housing-structure; and a shaft rotatably bearing directly in the bearing-passage of the said housing-structure; the convolutions of the said groove being walled off from each other by flat-faced bearing-lands, which latter actually support the weight of the said shaft; the direction of relative rotation between the said shaft and the said bearing-passage being such that the coating-surfaces effect the wiping of excess oil inwardly through

the said helical groove into the oil-chamber in the said housing-structure.

5. An oil-chamber construction of the class referred to, including: a housing-structure providing a closed oil-chamber therein and having a bearing-passage leading from its interior to its exterior; and a shaft rotatably bearing directly in the bearing-passage of the said housing-structure and provided with a helical oil-return groove the convolutions of which are walled off from each other by flat-faced bearing-lands, which latter actually support the weight of the said shaft; the direction of rotation of the said shaft with respect to the said bearing-passage being such that the coating-surfaces effect the wiping of excess oil inwardly through the said helical groove toward the oil-chamber in the said housing-structure.

10. An oil-chamber construction of the class referred to, including: a housing-structure providing an oil-chamber therein and having a bearing-passage leading from its interior to its exterior; and a shaft rotatably bearing directly in the bearing-passage of the said housing-structure and provided with a helical oil-return groove connecting to the interior of the oil-chamber within the said housing-structure the convolutions of which are walled off from each other by flat-faced bearing-lands, which latter actually support the weight of the said shaft; the direction of rotation of the said shaft with respect to the said bearing-passage being such that the coating-surfaces effect the wiping of excess oil inwardly through the said helical groove into the oil-chamber in the said housing-structure.

WALTER KOHLHAGEN.
